MEANS FOR EFFECTING RECIPROCATORY MOTION

Penrose R. Hoopes, Philadelphia, Pa., assignor to
 Super Speed Press Corporation, Bridgeton,
 N. J., a corporation of Delaware

Application February 20, 1945, Serial No. 578,843

5 Claims. (Cl. 74—571)

1

This invention relates to means useful in machines of various kinds for imparting motion to a member which is to be reciprocated. In connection with such means, it is the chief aim of my invention to make it possible to vary the throw of the reciprocated element between zero and the maximum for which the means is designed, with maintenance of a perfect balance in the parts in all positions of adjustment so that the machines in which my invention is incorporated can be operated at much higher speeds than heretofore with absence of vibration and with corresponding increase in productive output.

One way in which the foregoing and other objects and advantages may be readily realized in practice will appear from the following detailed description of the attached drawings, wherein

Fig. 1 is a fragmentary view in sectional elevation of a punching or stamping press conveniently embodying the reciprocating means of my invention.

Figs. 2 and 3 are detail sections on a larger scale taken as indicated by the angled arrows II—II and III—III in Fig. 1, showing the reciprocating means adjusted to impart the maximum throw.

Fig. 4 is a detail sectional view likewise on a larger scale taken as indicated by the angled arrows IV—IV in Fig. 1.

Figs. 5 and 6 are views like Fig. 4 showing the parts in different positions of adjustment.

Figs. 7, 8 and 9 are diagrammatic views, respectively corresponding to Figs. 4, 5 and 6.

With more detailed reference first more particularly to Fig. 1 of these illustrations, the press therein shown for convenience of exemplifying my invention has a frame with spaced rigid standards or columns 10 and 11 which are connected at the top by a bridging member 12. Disposed in the space between the standards or columns 10 and 11 of the frame is the vertically reciprocative member 13 of the press which has the form of a yoke with side members 15 and 16 and a connecting cross member 17 at the top.

The adjustable means provided for reciprocating the yoke 13 in accordance with my invention includes a rotary shaft with a journal portion 18 at one end, and with an integrally-formed laterally-offset crank extension 19 at the other end. The journal portion 18 of the shaft is rotatively supported in a bearing 20 suitably mounted in the standard 10, while the crank extension 19 is engaged and held within the eccentric bore of a bushing 21 which is rotative in a bearing 22 in

5 the standard 11 in line with the main bearing 20. In the illustrated instance, the shaft is driven through a clutch generally designated by the numeral 23 by a fly wheel 24 having belt grooves at 25; and an automatic brake comprehensively designated 26 is relied upon to stop the shaft upon disconnection of said clutch. The last described devices and other parts of the press except those about to be referred to, do not form 10 any part of the present invention and do not therefore need further mention.

Mounted on the crank extension 19 of the shaft with capacity for rotative adjustment thereon in a manner later on explained is a sleeve 27. Adjacent its ends, this sleeve 27 is formed with contiguous-eccentric enlargements 28, 29 and 28a, 29a, of which the latter are diametrically opposed to and counterbalance the former about the axis B of the crank portion 19 of the shaft 18. As shown, the eccentric enlargements 28 and 29 are centered on an axis C and extend through bearings 30 and 31 in the side portions 15 and 16 of the reciprocated member, while the eccentric enlargements 28a and 29a are centered on the shaft-bushing axis A. The sleeve 27 is moreover formed at its very ends with integral flanges 32 and 37 which are centered on the crank axis B. As further shown, the sleeve flange 32 abuts an eccentric flange 33 integrally-formed medially of the drive shaft 18 and centered in the crank axis B. The shaft flange 33 is made with a conical periphery for wedging action with a surrounding clamp ring 34 and has a shouldered portion 33a which snugly fits into a recess in the contiguous face of the sleeve flange 32. The shaft flange 33 is moreover provided with a circumferential series of tapped holes to receive the shanks of headed screws 35 passed through screw holes in the sleeve flange 32. The other sleeve flange 37 in turn abuts a concentric conical flange 38 on the bushing 21, the latter flange being provided with a shouldered portion 21a which snugly fits into a recess in the contiguous face of the flange 38. A clamp ring 39 surrounding the flange 38 is provided with a circumferential series of tapped holes for engagement by the shanks of headed screws 40 passed, as before stated, through the screw holes of the sleeve flange 37. Attention is directed to the fact that 45 the eccentricity of the enlarged portions 28, 29 of the sleeve 27 relative to the crank 19 is equal to the eccentricity of said crank extension 19 relative to the shaft; that is to say, the axis C is offset from the axis B by the same distance as the axis B is offset from the axis A. Secured by

screws 41 and 42 to the shaft and bushing flanges 33 and 38 respectively are weighted annular elements 43 and 44 which counterbalance said flanges and the crank portion 19 of the shaft 18. As shown the elements 43 and 44 are centered on the shaft-bushing axis A and have openings centered on the crank axis B to snugly receive the sleeve flanges 32 and 37.

With the sleeve 27 set as shown in Figs. 1-4, it will be seen that the eccentricity of the portions 28 and 29 of the sleeve 27 is added to that of the crank 19 so that maximum movement is imparted to the reciprocated element 13, the effective crank radius being as indicated by the arrow R in Fig. 7. To change the adjustment, the screws 35 and 40 are backed off to relieve the clamp rings 34 and 39 so that the sleeve 27 may be rotated in either direction about the crank 19 until the desired adjustment is had, whereupon said screws are re-tightened to hold such adjustment. The adjustment may be effected by means of a spanner wrench inserted into holes provided for that purpose in flanges 36 and 37. By turning the sleeve 27 through 180° from the position of Figs. 1, 3, 4 and 7 to the position of Figs. 5 and 8, the axis C is brought into coincidence with the shaft-bushing axis A with the result that the effective crank radius will be zero. Again, by turning the sleeve 27 through a smaller angle as exemplified in Figs. 6 and 9, the effective crank radius will be shortened to the distance R' and the movement of the member 15 correspondingly reduced.

Since, by reason of the described construction, the sleeve 27 is perfectly balanced about the crank axis B by the counterweighting at 28a and 29a, and the sleeve mass together with the crank extension 19 is perfectly balanced about the shaft axis A by the counterweighting at 43 and 44, it follows that the rotation of the drive shaft will be unattended by vibration for positions of adjustment of the crank throw. Accordingly machines in which the reciprocating means of my invention are employed can be safely operated at much higher speeds than heretofore possible and their output in turn correspondingly increased. Moreover due to the coaction between the shouldered portions 33a and 38a of the shaft and bushing flanges 33 and 38 and the recesses in the collar flanges 32 and 37, it will be seen that the crank extension 19 of said shaft and the sleeve 27 are effectively stiffened to withstand any forces tending to flex or bend them incident to high speed operation of the machines.

Having thus described my invention, I claim:

1. Means for effecting reciprocatory motion including an integrally-formed drive shaft element with a journal portion at one end, a laterally-offset crank extension at the other end, and a medially-located eccentric flange centered on the

crank axis; a bushing coaxial with the journal portion of the drive shaft, said bushing having an eccentric bore in which the end of the crank extension is engaged, and an eccentric flange 5 centered on the crank axis; bearings respectively for the journal portion of the shaft and the bushing; a sleeve mounted with capacity for rotative adjustment about the crank between the shaft flange and the bushing, said sleeve having an 10 eccentric enlargement for actuating a member which is to be reciprocated, and end flanges centered on the crank axis and respectively abutting the shaft and bushing flanges; clamp means operative to connect the sleeve flanges with the 15 shaft and bushing flanges to secure the sleeve in adjusted positions; and means whereby the sleeve is dynamically balanced about the crank axis, and whereby the crank and the sleeve are dynamically balanced about the shaft-bushing axis 20 for all rotatively-adjusted positions of said sleeve.

2. The invention defined in claim 1, wherein the displacement of the eccentric portion of the sleeve relative to the crank axis is equal to the displacement of said crank axis relative to the shaft-bushing axis.

3. The invention defined in claim 1, wherein the drive shaft and the bushing flanges have shouldered portions concentric with the crank axis which snugly fit into recesses in the contiguous faces of the corresponding sleeve flanges.

4. The invention defined in claim 1, wherein the peripheries of the shaft and bushing flanges are conical; wherein correspondingly bored clamp rings fit over said flanges; and wherein the 35 shanks of headed screws are passed through screw holes in the sleeve flanges and threadedly engage tapped holes in said clamp rings.

5. The invention defined in claim 1, wherein the balancing means include an integral eccentric 40 portion on the sleeve disposed diametrically opposite the eccentric enlargement for actuating the reciprocated member, and counterweight elements centered on a shaft axis and secured to the shaft and the bushing flanges, said elements 45 having circular openings centered on the crank axis and fitting over said sleeve flanges.
